INVENTOR:

Edward Luft.

John C. Higdon
BY
ATTORNEY.

UNITED STATES PATENT OFFICE.

EDWARD LUFT, OF ST. LOUIS, MISSOURI.

METALLIC WINDOW-SCREEN.

1,339,464.

Specification of Letters Patent. Patented May 11, 1920.

Application filed February 10, 1919. Serial No. 276,026.

To all whom it may concern:

Be it known that I, EDWARD LUFT, a citizen of the United States, residing at St. Louis, in the State of Missouri, have invented certain new and useful Improvements in Metallic Window-Screens, of which the following is a specification containing a full, clear, and exact description, reference being had to the accompanying drawings, 10 forming a part hereof.

My invention relates to an improved all-metal window-screen, that is adjustable and transformable; and it consists in the novel construction and combination of parts here- 15 inafter particularly described and claimed.

The object of my invention is to provide an improved all-metal window screen that shall be adjustable to different sizes of windows; transformable to either a "half" 20 window or a "whole" window; that shall be simple, cheap, and reliable, as well as durable; and that shall be devoid of all tacks, screws, or nails, the woven-wire fabric being secured in place by "crimping" the 25 metal of the members of the frame upon its edges.

In the drawings,

Figure 1 is a front elevation of one of my sliding frames, detached from its connect- 30 ing-bar, and separated from its companion frame.

Fig. 2 is a vertical section through the same, taken on the line 2—2 of Fig. 1, the parts being shown thicker than they are in 35 actual practice, as compared to their size, for the sake of clearness.

Fig. 3 is a detail plan-view, partly in section, of one corner (the top left-hand corner) of the sliding frame shown in Fig. 1, 40 looking in the direction indicated by the arrow 3.

Fig. 4 is a detail inverted plan-view of one of the connecting-bars, that is used in coupling two sliding frames.

Fig. 5 is a detail cross-section through the 45 said bar, taken on line 5—5 of Fig. 4.

Fig. 6 is a detail edge-view of said bar, partly in section, the section being taken on line 6—6 of Fig. 4.

Fig. 7 is a detail view of the top left-hand corner of the frame shown in Fig. 1, with the connecting-bar, or slide-bar, in place thereon.

Fig. 8 is a cross-section, partly broken 50 away, of a pair of sliding frames arranged in sliding relation, back-to-back, and con-

nected at their opposite edges by the opposite connecting or slide-bars, and

Fig. 9 is an elevation of the pair of connected sliding frames, transformed to cover 60 an entire window, in a window-frame.

In the present illustration of my invention, I provide a pair of the sliding frames, like the one shown in Fig. 1, which are made entirely of metal, and composed of opposite end-bars 1, opposite side-bars 2, and woven-wire fabric 3 secured to said bars solely by "crimping," and without the use of tacks, screws, nails or other fastenings, as shown more clearly in Figs. 2 and 8.

Said end and cross bars 1 and 2 are each made by taking a suitable strip of sheet-metal and doubling it upon itself longitudinally, and then bending the doubled portions again longitudinally of the strip, until the free edges extend at a right-angle to the main doubled body or guide-flange 4, the edges of the said fabric 3 being previously placed in the space between said doubled parts, so that when said parts are forcibly 80 pressed into contact with said fabric the latter will be secured effectually and permanently in said space solely by said operation, which I term "crimping," no other fastening for said fabric being necessary; the 85 fabric being of course stretched tightly before its edges are secured to said bars.

As shown in Figs. 1 and 9, the end portions of said bars 1 and 2 overlap at the corners of the frame, and they may be se- 90 cured together thereat by soldering, brazing, or by welding, in a well-known manner, in case it is desired to make the frames very stiff, and to hold them permanently in a rectangular form; but ordinarily the "crimp- 95 ing" operation will hold them in rectangular form, without resorting to soldering or the like.

In use, a pair of sliding frames, as above described, are placed back-to-back, as shown 100 in Figs. 8 and 9, with their opposite pairs of guide-flanges 4 projecting in opposite directions at opposite edges of said frames, and slidingly connected thereat by means of metallic slide and guide bars, that are shown 105 in detail in Figs. 4, 6 and 8. The said slide and guide bars, composed of said guide- flanges 5 on their opposite edges and other parts hereinafter described, extend the full length of the upper and lower bars 1 of said 110 sliding frames, and act as a stiffening and protection to said upper and lower bars,

throughout the length of the latter, except when the sliding frames are extended as shown in Fig. 9.

Said slide and guide bars are composed of a strip of metal formed with guide-flanges 5 at its opposite edges, formed by bending the edges as shown in Fig. 5, so that a space 6 will be provided between said bent edges and the body of the metal, in which space the said guide-flanges 4 of said frames will freely slide, in adjusting said frames to fit any size of window-frame. Integral end-lugs 8, on the opposite ends of the said slide and guide bars, are bent inwardly at right-angles to the body of said bars, and engage the adjacent vertical bars 2 of said sliding frames, for the purpose of locking said slide bars in position upon their respective sliding frames—that is, to lock each of said slide bars to the particular frame of which it forms a specific part, and with which it slides.

In Fig. 9 I have shown my pair of frames transformed to cover the entire window-opening of the common window-frame 7, in which case the screen-carrying frames are slid vertically upon each other, until they fill the entire window.

In Fig. 9 the screen frames are shown turned on their sides, so that the said top and bottom bars 1 are located at the sides of the window, while the said cross bars 2 occupy positions at the top and bottom of the sliding frames.

In cases where it is not desired to fill the entire window, the pair of sliding frames are adjusted horizontally upon each other, and are to be placed horizontally in the space

below the raised lower sash (not shown), in the usual manner in which common pairs of sliding screens are used.

The operation of my invention will be obvious from the above description.

I claim:

1. An improved adjustable sheet-metal window-screen, comprising top and bottom slide-bars extending the full length of the screen-frame to which they are attached, and a pair of sheet-metal screen-frames carrying woven-wire fabric and slidably-connected to said top and bottom slide-bars.

2. An improved adjustable metallic window-screen, comprising a pair of sheet-metal frames having opposite fabric-holding bars at their edges; opposite ones of said bars having guide-flanges extending at a right-angle from same, in opposite directions in the same plane, when said frames are placed back-to-back; woven-wire fabric secured at its edges to said bars; and oppositely-located slide-bars fixed one upon one edge of one of said frames and the other upon the opposite edge of the other frame, and provided with guide-spaces in which slide the said guide-flanges of said frame bars, during the adjustment of said frames, said slide-bars extending the full length of said frames.

In testimony whereof I have signed my name to this specification in presence of two subscribing witnesses.

EDWARD LUFT.

Witnesses:

FRANCES HOOVER ROSENBAUM,
JOHN C. HIGDON.
